HERMAN SCHLAICH, OF LONG ISLAND CITY, NEW YORK.

WINDING DEVICE.

Application filed June 6, 1924. Serial No. 718,241.

The present invention relates to a winding device, and, is more particularly directed toward the provision of a winding device adapted for winding a double helical coil, 5 i. e. a coil having a plurality of layers.

In many places in the arts space requirements dictate the use of small coils. One example of such is to be found in delicate pressure responsive instruments, such as 10 distance-type thermometers. In such an instrument the coil, preferably made of flat tubing, is distorted by the application of internal pressure, and the indicating means is operated in response to this distortion. 15 Inasmuch as the amount of movement available depends upon the length of the material wound into the coil, and the available space permits only a small coil, it has been found desirable to provide coils having at least two 20 layers.

The present invention contemplates the provision of a machine suitable for winding coils having a plurality of layers.

While the embodiment to be herein described in detail is more particularly designed for winding the pressure responsive coils such as above-mentioned, it is of course to be understood that this is merely a convenient illustrative embodiment of the invention, and that the invention contemplates providing a machine for winding various other coils.

In the drawing wherein this embodiment is illustrated:

Fig. 1 is a sectional view with parts in elevation, showing the parts in the position assumed when a double coil has been completed;

Fig. 2 is an elevational view with the parts in the position assumed during the winding of the first layer of the coil;

Fig. 3 is an elevational view of the coil winding mandrels in the position shown in Fig. 1;

Fig. 4 illustrates a modified inner mandrel; and

Figures 5 and 6 are end and side elevational views of a coil such as may be wound on the present embodiment of the invention.

A frame 10, adapted to be suitably fastened so as to be stationary, is provided with two spaced uprights 11 and 12. These uprights are provided with coaxial bearing holes 14 and 15 for the movable parts of the winding mechanism. The bearing hole 14

in the left hand bearing is larger than the bearing hole 15 in the right hand bearing, as it is designed to accommodate a large diameter sleeve or outer mandrel 17. This sleeve is rotatably carried in the bearing hole 14, 60 and collars 18 and 19, fastened to the sleeve, as by lock screws 20, hold it firmly in place relative to the upright.

The outer sleeve or mandrel is provided with a slot 21 in which a key 22 is carried. 65 For convenience this key and slot are located intermediate the collars 18 and 19. The inside diameter of the outer sleeve is preferably the same as the diameter of the hole 15, and an inner mandrel, in the form of a 70 shaft 23 is passed through these parts. This mandrel or shaft is provided with a long keyway 24 to accommodate the key 22. The keyway preferably extends to the left end 25 of the mandrel so that the mandrel may 75 be readily slid into place without removing the key 22. This end of the inner mandrel is preferably provided with a spiral-stepped portion 26 of increasing diameter for a purpose to be described, and an abutment or 80 stop 30 is attached to the end of the mandrel. As here shown, this stop is in the form of a cylindrical flange or head having an outside diameter approximately equal to that of the outer mandrel. The stop is removably attached by threading it into a tapped hole 31 in the mandrel.

The shaft or mandrel 23 is also provided with adjustable stops 32 and 33 in the form of collars which limit the sliding movement 90 of the mandrel relative to the frame. Fig. 1 shows the mandrel in the extreme right-hand position, while Fig. 3 shows it in the extreme left position. Any convenient device such as a crank 34 may be provided for 95 turning the shaft 23 on its axis.

In winding a coil on the present machine, the end 35 of the strip 36 is inserted into a slot or keyway 37 in the inner mandrel to anchor it to the mandrel and power is applied to turn the mandrel. The operator, or suitable guides, not shown, holds the strip in such a way that a smooth regular cylindrical coil A is tightly wound onto the mandrel in the manner indicated in the 105 drawings. As the convolutions approach the left end 25 of the mandrel the strip is wound upon the spiral stepped portion 26 so as to gradually increase the diameter of this portion of the coil. At or before this 110

time, the inner mandrel is moved to the right to withdraw the convolutions already formed into the inside of the outer mandrel 17, which is counter bored as shown at 38 5 to accommodate the partly wound coil. The adjustment of the stop 32 is preferably such that the stop or abutment 30 is spaced from the left end 39 of the outer mandrel a distance slightly greater than the width 10 of the strip being wound. This space provides room for superposing the windings so as to coil the strip to a larger diameter. The flanged stop 30 will redirect the strip and cause the end convolutions of the coil 15 to be plane instead of spiral. In order to further increase the diameter of the coil to the outside diameter of the mandrel 17, and to cause the outer windings B to again be spiral, the end 39 of the outer mandrel is 20 preferably provided with a spiral-stepped portion 40 as shown. The winding operation is continued, the strip being suitably guided to form smooth coils or convolutions. The two mandrels are coupled together for 25 bodily rotation on account of the key and slot interconnecting them, and hence they both rotate during the winding of the inner and the outer coils.

When the winding operation has been 30 completed, the coil is cut away from the strip, whereupon it may be readily removed from the mandrels after the head or abutment 30 has been removed from the mandrel and the mandrel and coil moved to the left 35 to withdraw the coil from the outer mandrel. The resiliency of the material will cause the convolutions to loosen from the mandrels and allow one to readily remove the complete double coil from the machine, 40 the inner end 35 of the coil sliding out through the slot 37 which extends to the end of the mandrel.

The completed coil is shown in Figures 45 and 6, from which it will appear that a long strip has been wound into a very small space, the coils being such that the expansion in all parts is additive. When the strip is flat capillary tubing, as shown, the resulting coil is well suited for use as the pressure 50 responsive element of distance type thermometers.

According to the modification shown in Fig. 4, the removable head or abutment 30 carries the spiral-stepped portion 26' by 55 which the diameter of the coil is gradually increased. The removal of the abutment carries this stepped portion along with it, so that the inner convolutions of the coil may be removed without expanding them to 60 pass the same.

It is of course obvious that the various parts of the machine may be varied or omitted as desired so as to fit it for winding various kinds of coils.

65 It is obvious that the invention may be

embodied in many forms and constructions, and I wish it to be understood that the particular form shown is only one of the many forms. Various modifications and changes being possible, I do not limit myself in any way with respect thereto.

What I claim is:

1. In a coil winding machine, in combination, means for winding a helical coil having a plurality of convolutions comprising a 75 mandrel, means for winding a second helical coil outside the first coil, including a rigid sleeve mandrel to enclose the first coil, and means rigidly supporting the mandrels with provision for relative axial movement. 80

2. In a coil winding machine, in combination, means for winding a helical coil having a plurality of convolutions comprising a mandrel, means for winding a second helical coil outside the first coil, including a rigid 85 sleeve mandrel to enclose the first coil, a removable abutment carried by one of said mandrels for preventing the removal of the coils from both of the winding means, and means rigidly supporting the mandrels with 90 provision for relative axial movement.

3. A coil winding machine having means for winding a helical coil having a plurality of convolutions, means for increasing the 95 diameter of the end convolutions, and means for winding a second helical coil outside the first coil, comprising a rigid sleeve mandrel and means for relatively moving the first coil and the sleeve mandrel in the direction 100 of the axis of the latter. 100

4. A coil winding device comprising inner and outer mandrels, means coupling the mandrels together for bodily rotation, the outer mandrel being in the form of an open-ended sleeve of larger diameter than the 115 other, the inner mandrel being slidable within the outer mandrel and extending beyond the open end thereof.

5. A coil winding device having two mandrels coupled together for bodily rotation, 110 the outer mandrel being in the form of an open-ended sleeve of larger diameter than the other, the inner mandrel being slidable within the outer mandrel and extending beyond the open end thereof, and a stop to 115 prevent withdrawing the end of the inner mandrel inside the outer mandrel.

6. A coil winding device comprising inner and outer mandrels, means coupling the mandrels together for bodily rotation, the 120 outer mandrel being in the form of an open-ended sleeve of larger diameter than the other, means fixedly supporting the outer mandrel, the inner mandrel being slidable within the outer mandrel and extending beyond the open end thereof, and a removable head for the inner mandrel. 125

7. A coil winding device having two mandrels coupled together for bodily rotation, the outer mandrel being in the form of an 130

open-ended sleeve of larger diameter than the other, the inner mandrel being slideable within the outer mandrel and extending beyond the open end thereof, a stop to prevent withdrawing the end of the inner mandrel inside the outer mandrel, and a removable head for the inner mandrel.

8. A coil winding device having two mandrels coupled together for bodily rotation, the outer mandrel being in the form of an open-ended sleeve of larger diameter than the other, the inner mandrel being slideable within the outer mandrel and extending beyond the open end thereof, each of the mandrels having provisions for gradually increasing the diameter of the coil as it passes from the inner mandrel to the outer mandrel.

9. A coil winding device having two mandrels coupled together for bodily rotation, the outer mandrel being in the form of an open-ended sleeve of larger diameter than the other, the inner mandrel being slideable within the outer mandrel and extending beyond the open end thereof, and a stop to prevent withdrawing the end of the inner mandrel inside the outer mandrel, the inner mandrel being sufficiently spaced inside the outer mandrel to accommodate the windings of a coil.

10. A coil winding device having two mandrels coupled together for bodily rotation, the outer mandrel being in the form of an open-ended sleeve of larger diameter than the other, the inner mandrel being slideable within the outer mandrel and extending beyond the open end thereof, and a stop to prevent withdrawing the end of the inner mandrel inside the outer mandrel, each of the mandrels having provisions for gradually increasing the diameter of the coil as it passes from the inner mandrel to the outer mandrel.

11. A coil winding device having two mandrels coupled together for bodily rotation, the outer mandrel being in the form of an open-ended sleeve of larger diameter than the other, the inner mandrel being slideable within the outer mandrel and extending beyond the open end thereof, and a stop to prevent withdrawing the end of the inner mandrel inside the outer mandrel, the inner mandrel having a slot adapted to receive the inner end of the coil, said slot extending to the end of the mandrel to permit sliding the coil off the mandrel.

12. A coil winding device having two mandrels coupled together for bodily rotation, the outer mandrel being in the form of an open-ended sleeve of larger diameter than the other, the inner mandrel being slideable within the outer mandrel and extending beyond the open end thereof, and a stop to prevent withdrawing the end of the inner mandrel, the inner mandrel being sufficient-

ly spaced inside the outer mandrel to accommodate the windings of a coil, each of the mandrels having provisions for gradually increasing the diameter of the coil as it passes from the inner mandrel to the outer mandrel.

13. A coil winding device having two mandrels coupled together for bodily rotation, the outer mandrel being in the form of an open-ended sleeve of larger diameter than the other, the inner mandrel being slideable within the outer mandrel and extending beyond the open end thereof, and a stop to prevent withdrawing the end of the inner mandrel inside the outer mandrel, the inner mandrel being sufficiently spaced inside the outer mandrel to accommodate the windings of a coil, the inner mandrel having a slot adapted to receive the inner end of the coil, said slot extending to the end of the mandrel to permit sliding the coil off the mandrel.

14. A coil winding device having two mandrels coupled together for bodily rotation, the outer mandrel being in the form of an open-ended sleeve of larger diameter than the other, the inner mandrel being slideable within the outer mandrel and extending beyond the open end thereof, and a stop to prevent withdrawing the end of the inner mandrel inside the outer mandrel, the inner mandrel being sufficiently spaced inside the outer mandrel to accommodate the windings of a coil, each of the mandrels having provisions for gradually increasing the diameter of the coil as it passes from the inner mandrel to the outer mandrel, the inner mandrel having a slot adapted to receive the inner end of the coil, said slot extending to the end of the mandrel to permit sliding the coil off the mandrel.

15. In a coil winding device, a frame, a mandrel mounted in the frame for rotation and for bodily movement along its axis, said mandrel extending beyond the frame and having a longitudinal slot extending to the end thereof, a removable head at the end of the mandrel, stops for limiting the bodily movement of the mandrel in the frame, an outside sleeve keyed to the mandrel and rotatably mounted in the frame, said sleeve extending beyond the frame nearly to the end of the mandrel when the mandrel is in its inner position.

16. In a coil winding device, a frame, a mandrel mounted in the frame for rotation and for bodily movement along its axis, said mandrel extending beyond the frame and having a longitudinal slot extending to the end thereof, a removable head at the end of the mandrel, stops for limiting the bodily movement of the mandrel in the frame, an outside sleeve keyed to the mandrel and rotatably mounted in the frame, said sleeve extending beyond the frame nearly to the

end of the mandrel when the mandrel is in its inner position, and having a spiral stepped portion for changing the diameter of the coil from the diameter of the mandrel 5 to the diameter of the sleeve.

17. In a coil winding device, a frame, a mandrel mounted in the frame for rotation and for bodily movement along its axis, said mandrel extending beyond the frame and 10 having a spiral stepped portion at the end thereof for gradually changing the diameter of the coil, a longitudinal slot extending to said end, a removable head at the end of the mandrel, stops for limiting the bodily movement 15 of the mandrel in the frame, an outside sleeve keyed to the mandrel and rotatably mounted in the frame, said sleeve extending beyond the frame substantially to the stepped portion of the mandrel when 20 the mandrel is in its inner position.

18. In a coil winding device, a frame, a mandrel mounted in the frame for rotation and for bodily movement along its axis, said mandrel extending beyond the frame and 25 having a spiral stepped portion at the end thereof for gradually changing the diameter of the coil, an outside sleeve keyed to the mandrel and rotatably mounted in the frame, said sleeve extending beyond the frame substantially to the stepped portion of the mandrel when 30 the mandrel is in its inner position, and having a spiral stepped portion for changing the diameter of the coil from the maximum diameter of the mandrel to the 35 diameter of the sleeve.

19. In a coil winding device, a frame, a mandrel mounted in the frame for rotation and for bodily movement along its axis, said mandrel extending beyond the frame and 40 having a spiral stepped portion at the end thereof for gradually changing the diameter of the coil, a longitudinal slot extending to said end, a removable head at the end of the mandrel, stops for limiting the bodily movement 45 of the mandrel in the frame, an outside sleeve keyed to the mandrel and rotatably mounted in the frame, said sleeve extending beyond the frame substantially to the stepped portion of the mandrel when 50 the mandrel is in its inner position, and having a spiral stepped portion for changing the diameter of the coil from the maximum

diameter of the mandrel to the diameter of the sleeve.

20. A coil winding device having a rotatably mounted mandrel having a cylindrical portion for winding a helical coil and a spiral stepped portion at the end thereof for gradually changing the diameter of the coil. 55

21. A coil winding device having a rotatably mounted mandrel having a spiral stepped portion at the end thereof for gradually changing the diameter of the coil, and a longitudinal slot extending to said end. 60

22. A coil winding device having a rotatably mounted mandrel having a spiral stepped portion at the end thereof for gradually changing the diameter of the coil, and a removable head of larger diameter 70 than the mandrel fastened to the end of the mandrel.

23. A coil winding machine comprising an inner mandrel, an outer mandrel encircling the inner mandrel, and means connected to the mandrels and positively driving the inner mandrel and the outer mandrel. 75

24. A coil winding machine comprising an inner mandrel, an incompressible outer mandrel surrounding the inner mandrel, and means supporting and guiding said mandrels for axial movement relative to the other. 80

25. A coil winding machine comprising an inner mandrel, and an incompressible outer mandrel surrounding the inner mandrel, and means rigidly supporting and maintaining the mandrels in spaced, coaxial relation. 85

26. A coil winding machine comprising a cylindrical inner mandrel, a circumferentially continuous outer sleeve mandrel surrounding the inner mandrel and spaced therefrom, means for driving one of said mandrels, and a sliding key connection between said mandrels, permitting them to have relative movement axially but compelling them to rotate in unison. 90

27. A coil winding machine comprising an inner mandrel, an outer mandrel, and means for withdrawing one of said mandrels axially with reference to the other. 100

In testimony whereof I have affixed my signature to this specification.

HERMAN SCHLAICH.
